UNITED STATES PATENT OFFICE

103,859

DESIGN FOR A COMBINED DISPLAY RECEPTACLE AND MERCHANDISE RECEIVING CONTAINER

Hans Ramel, Cleveland, Ohio

Application January 29, 1936, Serial No. 60,876

Term of patent 7 years

To all whom it may concern:

Be it known that I, Hans Ramel, a citizen of the United States, residing at Cleveland, in the county of Cuyahoga and State of Ohio, have invented a new, original, and ornamental Design for a Combined Display Receptacle and Merchandise Receiving Container, of which the following is a specification, reference being had to the accompanying drawing, forming part thereof.

The figure is a perspective view of the com-

bined display receptacle and merchandise receiving container showing my new design.

The opposite sides of the article are substantially the same as those shown in the figure.

I claim:

The ornamental design for a combined display receptacle and merchandise receiving container, as shown and described.

HANS RAMEL.
